US00D731203S

(12) **United States Design Patent**
Watson et al.

(10) **Patent No.:** **US D731,203 S**
(45) **Date of Patent:** **** Jun. 9, 2015**

(54) **FLUID CARTRIDGE**

(71) Applicants: **Ben James Watson**, Hertfordshire (GB);
Neil Baron, London (GB)

(72) Inventors: **Ben James Watson**, Hertfordshire (GB);
Neil Baron, London (GB)

(73) Assignee: **NSE Products, Inc.**, Provo, UT (US)

(**) Term: **14 Years**

(21) Appl. No.: **29/473,250**

(22) Filed: **Nov. 20, 2013**

(51) LOC (10) Cl. **23-02**

(52) U.S. Cl.

USPC **D6/542**

(74) Attorney, Agent, or Firm — Dorsey & Whitney LLP

(57) **CLAIM**

The ornamental design for a fluid cartridge, as shown and described.

DESCRIPTION

FIG. 1 is a front view of the fluid cartridge, also showing the top.

FIG. 2 is a left side view of the fluid cartridge.

FIG. 3 is a right side view of the fluid cartridge.

FIG. 4 is a back view of the fluid cartridge.

FIG. 5 is a top view of the fluid cartridge; and,

FIG. 6 is a bottom view of the fluid cartridge.

The broken lines in the drawings are for the purposes of illustrating environment only, and form no part of the claimed design.

1 Claim, 5 Drawing Sheets
